UNITED STATES PATENT OFFICE.

ROBERT GRAHAM FOTHERGILL, OF TEMPLE, ENGLAND.

DEVICE FOR CONTROLLING AND REGISTERING THE ISSUE OF CHECKS OR PASSES IN THEATERS.

No. 800,096.

Specification of Letters Patent.

Patented Sept. 19, 1905.

Application filed November 3, 1904. Serial No. 231,236.

To all whom it may concern:

Be it known that I, ROBERT GRAHAM FOTHERGILL, a subject of the King of Great Britain, and a resident of 3 Brick Court, Temple, in the county of Middlesex, England, have invented a new and useful Device for Controlling and Registering the Issue of Checks or Passes in Theaters, of which the following is a specification.

10 My invention relates to an improved device or apparatus by which the checks or passes ordinarily given in exchange for the money paid for the admission—for instance, to a theater or other place of amusement—are delivered to the persons entitled to them one by one in succession, while the number of checks or passes so issued is automatically recorded; and the objects of my improvements are, first, to deliver a check or pass to each 15 person paying the proper amount for it; second, to register the number of checks or passes so delivered; third, to insure the proper correspondence between the amount of money received and the number of checks or passes issued. I attain these objects by the mechanism illustrated in the accompanying drawings, in which—

Figure 1 is an elevation of the back of the apparatus. Fig. 2 is a vertical transverse section through the apparatus. Fig. 3 is a top view, on a larger scale, of one of the checks or passes to be delivered to the persons paying for them. Fig. 4 is a view from above of the delivering-slide. Fig. 5 is a view from below of the plate which covers the delivering-slide.

Similar letters refer to similar parts throughout the several views.

It is to be understood that the apparatus is 40 only available for delivering checks or passes serving to admit the holders to seats or positions for each of which the same amount of money has been paid, so that a separate apparatus will be required for delivering the 45 checks at each place where a different specified sum has to be paid.

a is a frame fitted and fixed upon the base or foundation *b* in the front of the box or office occupied by the attendant who receives 50 the money.

c is an opening shown closed below by a series of openings *d* sufficiently large to take through them the largest coin which can be used, but not large enough to allow the checks

or passes which are to be delivered to pass 55 through them. The upper part of the opening *c* is shown closed by wire-netting *e* of sufficiently small mesh, and *f* is a window in the upper part of the front *a*. In front of the openings *d* is a ledge or counter at *g* to receive the money passed in from the other side of the openings by the persons purchasing 60 checks.

Upon the base *b* of the apparatus, adjoining the opening *c*, but situated farther back from the front of the apparatus, is a strong box or case *h*, fixed upon a bottom support *i* on the base *b*. Upon the open top of the box *h* is fixed a plate *j*, provided with longitudinal guides *k* *k'* at right angles to the back of the apparatus, in which slides freely a sliding plate *l*, which is kept in its position by a covering-plate *m*, between which and the plate *j* a slit is left at the back through which the end of the sliding plate *l* projects. This projecting end is formed with pins *n*, Fig. 4, which serve as a hinge upon which the upper end of the vertical arm *o* of a bell-crank lever *p* is hinged, which turns upon a horizontal pivot *q*, carried in brackets *r*, fixed upon the base or support *i*. The horizontal arm *s* of the bell-crank *p* has its upper side formed as a thumb-piece by which it can be depressed by the attendant who receives the money and issues the corresponding checks, and it is 85 pressed up by a spring *t*. Two vertical parallel guides *u* *u'* are firmly fixed at their lower ends upon the top of the box *h*, and from their upper end is suspended freely by a pin *v* a straight bar *w*, triangular in section, the 90 lower end of which hangs down nearly to the top of the sliding plate *l*, and upon it are arranged one above the other, so as to slide freely upon it, a sufficient number of thin triangular plates *x*, (shown in plan on a larger 95 scale in Fig. 3), having through them a triangular hole *y*, through which the bar *w* passes. The covering-plate *m* also has through it a triangular hole *y*, through which one or more of the checks *x* drop freely, and the sliding plate *l* also has a corresponding hole *z*, into which the lowest check drops when the sliding plate is pushed into its normal position by the spring *t*. The fixed plate *j*, which covers the top of the box *h*, also has a similar triangular hole *A* through it, upon the edge of which the lowest check rests in the normal position of the sliding plate *l*, the hole *A* being 100 105

somewhat nearer the back of the apparatus than that through the upper plate *m*. When, however, the sliding plate *l* is drawn out by depressing the arm *s* of the bell-crank *p*, the 5 lowest check is drawn forward until it drops through the hole *A* in the plate *j* and falls into the recess *B* in the box *h*. The bottom of this recess is inclined down, as shown in dotted lines at *C*, Fig. 1, so that the check passes 10 down it and through an opening *D*, Fig. 1, and is delivered upon or into a receiving plate or holder *E* of any suitable shape, from which it is removed by the person who has paid the money. The checks *x* instead of being triangular may be of circular or any other desired 15 shape, of such size that they cannot pass through the openings *d*.

Upon the upper side of the covering-plate *m*, which covers the box *h*, is formed a dove-tailed groove in which slides parallel with the sliding plate *l* a small sliding piece having a downward projection *F*, which passes down through notches *M M* and is moved forward by the edge of the lowest check when the latter is moved out by the sliding plate and is returned to its place by a spring *G*, carried on the plate *m* when the sliding plate is returned, and this sliding plate *F* has a vertical groove or recess *H* on its upper surface, into 20 which fits freely a crank-pin *I* at the end of an oscillating arm *J*, which as it oscillates operates a counting device *K* of any of the well-known kinds, by which the number of oscillations, and consequently the number of checks 25 delivered, are counted and registered. This counting device *K* is shown fitting stiffly into a horizontal dovetailed guide *L*, so that it can be readily removed and replaced or changed when desired, and the act of with- 30 drawing it may release a stop which prevents any further delivery of checks until it is replaced. The counting device and the parts connected with it are inclosed and locked in a cover. (Not shown in the figures.) When 35 the pile of checks is exhausted, the bar *w* can be readily lifted out and a fresh one filled with fresh checks substituted for it. The upper edge of the hole through the sliding plate *l* is shown slightly beveled.

50 The external shape of the apparatus may be varied as desired.

The bar *w* is shown triangular in section; but it may be of any other section.

In a modification of the check-issuing device 55 the thumb-piece *s* and bell-crank *p* may be omitted and the sliding plate *l* may be drawn out when required by the attendant by means of a handle upon its outer edge and returned by a spring when released.

60 I am aware that prior to my invention check controlling and registering devices have been used in which checks are issued in exchange for money, and I do not claim such devices broadly; but

What I claim as my invention, and desire to 65 secure by Letters Patent, is—

1. The combination, in a check issuing and registering device, of a frame *a* having openings *g* large enough for the coin paid for a check or pass to be handed in, but not large 70 enough for the checks themselves to pass through, the box *h*, cover *j*, with hole *A* to receive and fit the checks, cover *m* having a similar hole *y* situated a short distance in advance of the hole *A* in plate *l*, guides *k*, *k'* 75 below plate *j*, sliding plate *l* between *j* and *m*, hole *z* through sliding plate *l* to receive and fit the checks, vertical guides *u*, *u'*, thin checks or passes *x* piled between guides *u*, *u'*, holes *g* through checks *x*, bar *w* suspended 80 from top of guides *u*, *u'* and fitting freely in holes *y*, bell-crank *p* pivoted at *q*, pins *n*, *n'*, jointing sliding plate *l* to vertical arm *o* of bell-crank *p*, horizontal arm or thumb-piece 85 *s* of bell-crank *p*, spring *t* raising thumb-piece *s*, and bringing back sliding plate *l* under the pile of checks *x* after it has been withdrawn by pressure on the thumb-piece *s*, inclined space *B*, into which the check passes after falling through the sliding plate *l*, opening 90 *D*, through which the check is delivered upon the receiving-plate *E*, all substantially as set forth.

2. In a check issuing and registering device, the combination with plates *j* and *m*, having 95 holes through them fitting the checks or passes used, the hole in the upper plate *m* being in advance of the hole in the lower plate *j*, a sliding plate *l* having a similar hole through it and movable endwise by pressure upon the 100 thumb-piece *s* until the hole *z* through it, which normally corresponds with the hole in the upper plate *m* corresponds with the hole *A* through the lower plate *j*, and spring *t*, the registering device consisting of the sliding 105 piece having downward projection *F* with which the check in the slide *l* comes in contact, notches or recesses *M*, spring *G*, vertical groove or recess *H*, pin *I* on arm *J*, which operates a counting device *K*, by which the 110 number of oscillations are counted and registered, all substantially as set forth.

3. The combination in a device of the class described, of plates *j* and *m* having holes through them fitting the checks or passes used, 115 the hole in the upper plate *m* being in advance of the hole in the lower plate *j*, a sliding plate *l* having a similar hole through it, a handle on said plate *l* for moving the same outwardly and a spring for returning said plate when 120 the handle is released.

In witness whereof I have hereunto set my hand in the presence of two witnesses.

ROBERT GRAHAM FOTHERGILL.
